[57] CLAIM

The ornamental design for a remote control, as shown and
described.

DESCRIPTION

FIG. 1 is a right side elevational view of the remote control,
showing my new design, the left side being a mirror image
thereof;

FIG. 2 is a top perspective view thereof;

FIG. 3 is a bottom plan thereof;
FIG. 4 is a top plan view thereof, the broken line showing
of the knobs is for illustrative purposes only, and forms no
part of the claimed design;

FIG. 5 is a front view thereof; and,

FIG. 6 is a rear view thereof.
